UNITED STATES PATENT OFFICE.

RAY SMITH, OF PORTLAND, OREGON, ASSIGNOR TO RICHARD L. HARDIN, OF PORTLAND, OREGON.

DESIGN FOR A STATUETTE OR SIMILAR ARTICLE.

53,716.

Specification for Design.

Patented Aug. 19, 1919.

Application filed February 5, 1919. Serial No. 275,259. Term of patent 3½ years.

To all whom it may concern:

Be it known that I, RAY SMITH, a citizen of the United States, and a resident of Portland, in the county of Multnomah and State of Oregon, United States of America, have invented a new, original, and ornamental Design for a Statuette or Similar Article.

Reference is to be had to the accompanying drawing in which

Fig. 2 is a front view thereof.

I claim:

The ornamental design for a statuette or similar article, as shown.

RAY SMITH.
